DESIGN FOR A FLUORESCENT LAMP

Henry Dreyfuss, New York, N. Y., assignor to Hygrade Sylvania Corporation, Salem, Mass.,
a corporation of Massachusetts

Application March 22, 1941, Serial No. 99,781

Term of patent 7 years

To all whom it may concern:

Be it known that I, Henry Dreyfuss, a citizen of the United States, residing at New York, in the county of New York and State of New York, have invented a new, original, and ornamental Design for a Fluorescent Lamp, of which the following is a specification, reference being had to the accompanying drawing, forming part thereof.

The figure is a perspective view of a fluorescent
lamp showing my new design.

I claim:

The ornamental design for a fluorescent lamp,
as shown.

HENRY DREYFUSS.
